UNITED STATES PATENT OFFICE.

CARL H. CRAWFORD, OF WASHINGTON, DISTRICT OF COLUMBIA.

ENVELOP-OPENER.

1,027,994.

Specification of Letters Patent.

Patented May 28, 1912.

Application filed June 3, 1911. Serial No. 631,094.

To all whom it may concern:

Be it known that I, CARL H. CRAWFORD, a citizen of the United States, residing at Washington, in the District of Columbia, 5 have invented a new and useful Improvement in Envelop-Openers, of which the following is a specification.

This invention relates to improvements in envelop openers of that class wherein the 10 opener is attached to the envelop.

One of the most important features of this invention is the provision of an opener so arranged that the flap of the envelop can be unsealed without any way disrupting or 15 tearing the flap, the unsealing operation being preferably effected by disruption of the hardened gum or adhesive with which the flap is sealed.

My invention will be more fully described 20 in connection with the accompanying drawing and will be more particularly pointed out in and by the appended claims.

In the drawing:—Figure 1 is a view in side elevation showing an envelop with the 25 flap sealed and illustrating one embodiment of my invention; Fig. 2 is a similar view of the envelop showing the flap open.

As illustrated in the drawing, 1 designates the body of an envelop and 2 designates a 30 flap forming a part thereof. As shown the flap is formed as an integral part of the envelop. As illustrated, the flap is provided with a suitable adhesive or gum 3 extending along its margin and by means of which 35 it may be sealed to the body 1. In this particular form of my invention, as applied to this particular style of envelop, a cord or thread like opener 4 is attached to the flap 2 by the gummed or adhesive material originally 40 applied to the flap when the envelop is made. At least one end of the opener 4 should be exposed and this feature is accomplished by having at least one end actually project from between the flap and envelop 45 body so as to be grasped by the user. In the particular embodiment shown, both ends of the opener project slightly outwardly from beneath the flap.

It is desirable to adhere the opener to the 50 flap closely adjacent the inner margin 5 of the gummed or adhesive material, as illustrated in Fig. 2. It is also very desirable to have the opener extend substantially throughout the length of the gummed strip 55 2 and preferably in a manner to conform to the shape of said gummed strip 2.

It will be seen that when the gummed strip is moistened and the flap is sealed upon the body of the envelop, that the adhesive substance sealing the flap will also hold the 60 opener in position thereby avoiding any alteration in the shape or construction of the flap or envelop, and also entirely avoiding any auxiliary means for holding the opener. Furthermore the opener may readily be applied to the envelop when the flap is originally 65 gummed without substantially departing from the present methods used in manufacturing envelops.

Usually the outermost marginal portions 70 of the flap are moistened to a greater extent than the inner portions and therefor by disposing the opener near the inner portion 5 the danger of loosening the opener from the flap before the flap is sealed is entirely 75 avoided. However the slight application of moisture to the gummed or adhesive strip would never be sufficient to loosen the opener under any ordinary conditions.

It will be seen that when one of the exposed ends of the opener 4, Fig. 1, is pulled downwardly in the direction of the arrow, the opener will serve to disrupt the adhesive which seals the flap without in any way mutilating or destroying the flap itself. By 80 disposing the opener in the position shown only a slight portion 6, of the adhesive, will not be disrupted but it will readily be understood that a slight pressure on the freed margin of the flap will readily serve to 85 break the thin strip of adhesive and permit the flap to open and remain intact. It will also be obvious that the body of the envelop, adjacent the flap, will not in any way be injured. It will also be noted that as the 90 gummed portion serves as a holding means for the opener, it is most advantageous that the opener should be held substantially throughout the length of the gummed strip so that the opener itself will not be disengaged from the envelop until the sealing material has been substantially entirely disrupted, as otherwise the opener might be withdrawn under the pull imparted to 95 unseal the flap any time prior to complete 100 severance of the sealed margin thereof.

My invention can be embodied with great advantage in expensive stationary envelops used for formal announcements and other social matters where it is desirable to retain the envelop in good condition as a container for the contents. In this utility of 110

my invention the opener might take the form of a very fine thread of silk or other suitable material having a color appropriate to the tint of the envelop thereby making 5 the opener a feature of esthetic value to the attractiveness of the envelop, as well as an element of utility. Another highly useful function of my invention is in connection with the extremely larger sized envelopes 10 which are relatively expensive and which are very desirable for use in remailing. It is well known that the stability of an envelop is greatly impaired when the flap is disrupted or torn when opened as an intact 15 flap is an element of strength to the envelop during transmission.

The opener is completely detached when the flap is opened thereby.

It is desirable to use an opener of a non- 20 metallic character so that no objection would arise from its being accidentally caught by packages and other articles in transmission, and also to prevent any injury to the mail bags and inconvenience in handling.

25 While I have herein described and illustrated one particular embodiment of my invention it will be understood that I do not wish to be limited to this particular form shown except for such limitations as the 30 claims may import.

I claim:-

1. In combination with an envelop comprising a body and flap, of a cord-like opener attached to the flap by the gum or adhesive

originally applied thereto and having one 35 end exposed whereby the flap may be opened by disrupting the gum.

2. In combination with an envelop comprising a body and a flap sealed thereon, of a cord-like opener interposed between and 40 attached by the gum or adhesive with which the flap is sealed and having one end exposed whereby the flap may be opened by disrupting the gum.

3. In combination with an envelop comprising a body and flap sealed thereon, of a cord-like opener attached by an adhesive substance between the flap and body whereby the flap may be opened by disrupting the gum. 45

50 4. In combination with an envelop comprising a body portion and a flap portion, and a cord-like opener gummed to one of said portions and so disposed as to lie beneath the flap when the same is sealed on the body portion whereby the flap may be opened by disrupting the gum.

5. An envelop having a flap sealed thereon and means disposed beneath the flap for disrupting the sealing substance without injuring the flap or envelop. 60

Witness whereof I append my signature in the presence of two witnesses, at Washington, D. C., third of June, 1911.

CARL H. CRAWFORD.
